UNITED STATES PATENT OFFICE.

DONALD FRANK JOHNS, OF MARICOPA, CALIFORNIA.

DEEP-WELL PUMP.

Application filed October 17, 1924. Serial No. 744,151.

To all whom it may concern:

Be it known that I, DONALD F. JOHNS, a citizen of the United States, residing in Maricopa, in the county of Kern, State of California, have invented a new and useful Deep-Well Pump, of which the following is a specification.

This invention relates to deep-well pumps, and particularly to that type of pump in which a pump barrel or liner is lowered into the flow pipe on the pump rod, the liner being provided with means for anchoring it at the desired depth within the flow pipe. The general object of this invention is to provide improved means for effecting the anchoring of the liner when it arrives at the desired depth, and the improvement involves the cooperating construction of the flow pipe and liner; it is also an object of the invention to provide improved means for packing the liner against the wall of the flow pipe and thereby develop a considerable resistance to longitudinal movement of the liner in the flow pipe, my general purpose being, in this connection, to relieve the latching device of a large part of the up-thrust which the pump piston would otherwise transmit through the liner to the latching device; in other words, one of the functions of my liner packing is to relieve the stress on the latching device.

Further objects of the invention will appear hereinafter.

The invention consists in the novel parts and combination of parts to be described hereinafter, all of which contribute to produce an efficient deep-well pump.

A preferred embodiment of the invention is described in the following specification, while the broad scope of the invention is pointed out in the appended claims.

In the drawing:—

Fig. 1 is a vertical section through a casing and flow pipe, broken away, and illustrating the general arrangement of all of the parts of the invention.

Fig. 2 is a view similar to Figure 1, but upon an enlarged scale, and illustrating the construction of the flow pipe, the latching means and the packing means. This view shows the latching device in its latching position, that is to say, it shows the parts of this device in the relation they have when

the latching device has anchored the liner within the flow pipe. 55

Fig. 3 is a vertical section upon the same scale as Fig. 2, particularly illustrating the latching device but showing the same in its retracted position—that is to say, with the parts in the relation which they have when 60 the liner and pump rod are being lowered within the flow pipe.

Fig. 4 is a horizontal cross section taken on the line 4—4 of Figure 2 and particularly illustrating the further details of the 65 packing.

In the drawing, 1 represents an ordinary well casing within which a flow pipe 2 is located.

Within the flow pipe there is provided a 70 liner 3, the lower portion 4 of which operates as a pump barrel in which the pump piston 5 reciprocates. I provide means for latching the liner in the flow pipe, and this means preferably includes a latching device 6 (see Figure 2) including a dog, but preferably two dogs 7 which are guided outwardly in openings in the wall of the liner, the outer end of each dog having an inclined face 8. 75

When the flow pipe 2 is constructed, I connect in it a special connection or tube 9 which is provided with engaging means or socket-means to cooperate with the latch device. In the present instance this engaging means is in the form of a circumferential groove 10 which has an annular horizontal shoulder 11 at its side to cooperate with the upper sides of the latches or dogs 7 to prevent the liner from being moved upwardly 90 by the upward movement of the pump piston 5, after the liner has been anchored. The latches or dogs 7 are controlled by actuating members 12, each of which is in the form of a lever pivoted on a horizontal 95 rocker pin 13 mounted in the adjacent portion of the liner below the dogs, and these actuating levers are provided with means to actuate the latching device into its engaging position. In the present instance this means is in the form of two leaf springs 14 attached respectively to the lower ends of the levers 12 and thrusting against the inner face of the wall of the liner, see Figure 2. 100

The pump rod 15, which is disposed with-

in the flow pipe and which extends down from the mouth of the wall, is provided with suitable means to engage the latching device to hold the same in its retracted position while the liner is being lowered within the flow pipe. For this purpose, I provide the lower end of the pump rod with a mandrel 16, the upper end of which is formed into a tapered portion or substantially conical nose 17. This nose, being formed adjacent the rod, of course engages the inner sides of the levers.

When the liner is being lowered into the well, this conical nose is in engagement with heads 18 which are formed at the lower ends of the levers 12, see Figure 3. This operates to hold the levers so that they incline inwardly at their upper ends and hold the dogs 7 in a retracted position. Each dog 7 is formed with a head 19 and the upper end of each lever is bifurcated to engage the dog adjacent the head.

I provide cooperating engaging means between the liner and the flow pipe preferably located above the socket means 10, to stop the liner when the latching device comes into alignment with the cooperating engaging means of the flow pipe, that is to say, the circumferential groove 10. For this purpose I provide a shoulder within the flow pipe which engages a corresponding shoulder on the liner. In the present instance, I employ a bushing 20 (see Figure 3) which is countersunk in the inner face of the liner and provided on its inner face with an annular shoulder 21. The liner is provided on its outer side with an annular shoulder 22, which engages the shoulder 21 as the liner descends through the flow pipe. During this descent, the liner is supported through the agency of the levers 12, the heads 18 of which rest on the conical end 17 of the mandrel. Figure 3 shows the relation of the parts while the pump rod and liner are being lowered. As soon as the shoulder 22 strikes the shoulder 21, the downward movement of the liner stops and when this occurs the dogs 7 will be in alignment with the groove 10; then a further downward movement of the pump rod will carry the conical end 17 down past the heads 18 and the springs 14 will then operate the levers 12 to force the dogs out into engagement with the groove 10 and under the shoulder 11. The inclined end face 8 of each dog 7 enables it to slip readily past the shoulder 21. Each dog may be provided with a cross pin 23 or a collar to receive the outward thrust of the adjacent forked end of the lever when the lever is forcing the dog outwardly.

At the lower end of the liner a foot valve 24 is carried, past which the oil or other liquid flows upwardly into the lower end of the pump barrel 4. The lower end of the

piston 5 carries a lower valve 25 and the upper end of the piston carries an upper valve 26. The piston 5 is tubular so that its bore 27 operates as a duct to permit upward flow of the liquid in the piston on each down stroke of the pump. The oil that passes upwardly above the upper valve 26 is then forced up at each upstroke through the upper portion of the liner and past the mandrel 16. About opposite the mandrel and below the latching device I provide packing means for packing the liner within the flow pipe. This packing prevents leakage of oil down past the liner, but it also performs the function of fixing the liner to the flow pipe, so that a large part of the upward thrust on the liner, caused by the upward movement of the piston, will be taken up at this point, and this reduces the upward thrust which would otherwise be transmitted to the latches 7. In providing for this packing, I provide a special coupling 28 (see Figure 2), the lower end of which is secured to the upper end of the pump barrel, and the upper end of which is attached to a packing sleeve 29. The upper end of this packing sleeve is attached to the upper section 30 of the liner, which carries the latching device.

The sleeve 29 carries a soft packing ring 31 on its outer side and I provide means for admitting the liquid pressure to the inner face of the soft packing ring 31 so as to press it out forcibly against the inner face of the wall of the flow pipe. For this purpose I provide the outer side of the sleeve 29 with a circumferential groove 32 which communicates with the interior of the sleeve through one or more openings 32a.

With this construction, it will be evident that the liquid pressure due to the head of the liquid in the flow pipe, will press the soft packing outwardly. In order to hold the soft packing in place at each end, the coupling 28 is provided with an overhanging annular flange 33, which projects over the lower end of the packing ring, which is of reduced diameter at this point. In a similar manner, at the upper end of the sleeve 29 I provide a ring 34 which is threaded on the upper end of the sleeve, and this ring has a flange 35 at its lower end which engages over a similar reduced end at the upper end of the packing ring. The packing ring 31 is preferably made of soft rubber.

It is understood that the embodiment of the invention described herein is only one of the many embodiments this invention may take, and I do not wish to be limited in the practice of the invention, nor in the claims, to the particular embodiment set forth.

What I claim is:

1. In a pump for deep wells, the combina-

- tion of a liner, a flow-pipe having a bore receiving the liner, a latch-device including a dog mounted on the liner to anchor it in the flow-pipe, said flow-pipe having socket means to cooperate with the latch-device in anchoring the liner, actuating means for the latch-device with means for moving the latch device into its engaging position, a pump-rod having a mandrel cooperating with the actuating means to hold the latch-device in its retracted position in lowering the liner within the flow-pipe, said liner and said flow-pipe having cooperating engaging means located above the said socket means, 10 for stopping the downward movement of the liner when the latch device is opposite to the said socket-means of the flow-pipe, said actuating means for the latch-device operating upon a further downward movement of the pump-rod to permit the latch-device to engage the socket-means and thereby anchor the liner in the flow-pipe, said dog having an inclined outer face enabling the same to pass the engaging means on the 25 flow pipe.
2. In a pump for deep wells, the combination of a liner, a flow-pipe having a bore receiving the liner, a latch-device having a plurality of latching levers extending longitudinally of the liner mounted on the liner to anchor it in the flow-pipe, said flow-pipe having socket means to cooperate with the latch-device in anchoring the liner, actuating means for the latch-device with 30 means for moving the latch device into its engaging position, a pump-rod having a mandrel with a tapered portion adjacent the rod, having a face to engage the levers on their inner sides, and cooperating with the levers and the actuating means to hold the latch-device in its retracted position in lowering the liner within the flow-pipe, a bushing mounted in said flow-pipe and having a shoulder, said liner having a shoulder 35 cooperating with the first named shoulder to stop the downward movement of the liner when the latch-device is opposite to the said socket-means of the flow-pipe, said actuating means for the latch-device operating, upon a further downward movement of the pump rod, to permit the latch-device to engage the socket-means and thereby anchor the liner in the flow-pipe.
3. In a pump for deep wells, the combination of a liner, a flow-pipe having a bore receiving the liner, a latch-device mounted on the liner to anchor it in the flow-pipe, said flow-pipe having socket means to cooperate with the latch-device in anchoring 40 the liner, actuating means for the latch-device with means for moving the latch device into its engaging position, a pump-rod having a mandrel with a substantially conical face engaging with the actuating means and located adjacent the rod to hold the latch-device in its retracted position in lowering the liner within the flow-pipe, a bushing mounted in the flow-pipe, a coupling connected in the flow-pipe retaining the bushing, said bushing having a shoulder and said liner having a shoulder to cooperate with the first named shoulder to stop the downward movement of the liner when the latch device is opposite to the said socket means, said actuating means for the latch device operating, upon a further downward movement of the pump rod, to permit the latch-device to engage the socket means and thereby anchor the liner in the flow-pipe. 70
4. In a pump for deep wells, the combination of a liner, a flow-pipe having a bore receiving the liner, a pump-rod, means controlled by the pump-rod for latching the liner within the flow-pipe, a piston carried by the pump rod to reciprocate within the liner, said liner including a tubular packing sleeve, the interior whereof receives the liquid being pumped, said sleeve having an opening through the wall thereof, a soft packing ring surrounding the sleeve at the 75 said opening so that the liquid pressure within the sleeve forces the soft packing ring against the wall of the flow-pipe, and means for securing the ends of the soft packing ring. 80
5. In a pump for deep wells, the combination of a liner, a flow-pipe having a bore receiving the liner and having a circumferential groove on the inner face of its wall, a latch-device having movable engaging dogs mounted on the liner to engage the said groove and anchor the liner in the flow-pipe, actuating members for the dogs with means to move the dogs into their engaging position, a pump-rod having a piston with a mandrel having a substantially conical face adjacent the pump-rod above the piston engaging the latch-device and cooperating with the actuating members to hold the dogs retracted in lowering the liner within the flow-pipe, said liner and said flow-pipe having shoulders respectively operating to engage each other and stop the downward movement of the liner when the dogs are in alignment with the said 90 groove, said actuating members for the dogs operating upon a further downward movement of the pump-rod and mandrel, to actuate the dogs to latch the liner within the flow-pipe. 95
6. In a pump for deep wells, the combination of a liner, a flow-pipe having a bore receiving the liner, a latch-device having movable engaging dogs mounted on the liner to anchor the liner in the flow-pipe, said flow-pipe having socket means to cooperate with the dogs in anchoring the same, actuating members for the dogs with means to move the dogs into their engaging position, a pump rod with a piston and a 100

mandrel having a substantially conical face adjacent the rod above the piston, engaging the latch-device and cooperating with the actuating members to hold the dogs retracted in lowering the liner within the flow-pipe, said liner and said flow pipe having engaging means for stopping the downward movement of the liner when the dogs are in

alignment with the said socket means of the flow-pipe, said actuating members for the dogs operating upon a further downward movement of the pump-rod to actuate the dogs to latch the liner within the flow-pipe. ¹⁰

Signed at Huntington Beach, Cal., this 30th day of Sept. 1924.

DONALD FRANK JOHNS.
